(57) **CLAIM**

The ornamental design for a display screen with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is an image for a display screen with graphical user interface showing our new design.

The peripheral broken lines illustrate a display screen or portion thereof and form no part of the claimed design. The broken lines within the peripheral broken lines illustrate portions of the graphical user interface and form no part of the claimed design. The broken lines are directed to unclaimed portions. The color forms part of the claimed design.
